his Atty.

UNITED STATES PATENT OFFICE

LAWRENCE M. FORNCROOK, OF PITTSBURGH, PENNSYLVANIA, ASSIGNOR TO ELLIOTT COMPANY, OF PITTSBURGH, PENNSYLVANIA, A CORPORATION OF PENNSYLVANIA

METHOD AND APPARATUS FOR EFFECTING HEAT INTERCHANGE

Application filed May 3, 1927. Serial No. 188,470.

This invention relates broadly to the art of effecting a heat interchange between two fluids such, for example, as a gas and a liquid, and more particularly to methods and apparatus involving heat exchange of the type secured in condensers for the purpose of effecting condensation of a vapor or vapors.

It is customary in the art to which the present invention relates to effect the condensation of a vapor or vapors in a tubular condenser, the temperature of the condensate produced depending upon the construction and manner of operation of the condenser. In many cases, it is desirable to produce a condensate having a temperature materially lower than that at which condensation actually takes place. This is particularly true in the art of petroleum distillation, and the present invention has for one of its objects the provision of a method and apparatus effective for producing a condensate having a temperature below the actual condensation temperature.

In many cases vapors resulting from the destructive distillation of oil must be condensed at temperatures so high that it would be extremely dangerous to remove and store the condensate at such temperatures due to the possibility of trouble resulting from contact therewith of the oxygen in the air.

It is well known to those skilled in the art that in the practical condensation of any vapor, especially at pressures lower than atmospheric, some non-condensable gas is always present in the condenser. This gas is sometimes liberated in the process of distillation, and nearly always is in evidence, by reason of infiltration from the atmosphere due to unavoidable leaks and the difference in pressure conditions within and without the condenser where condensation is carried on at pressures lower than atmospheric. In the usual operation of condensers, this condition is decidedly objectionable, and in order to permit the desired operation thereof, there is provided a gas vent at the end of the zone of condensation. Where the condenser is being operated at pressures higher than atmospheric, the vent usually discharges directly to the atmosphere, while in cases of op-

eration at pressures below atmospheric, a suitable evacuating pump is utilized.

In accordance with the present invention, I reverse, to a certain extent, the usual methods of condenser operation and take advantage of such non-condensable gases for obtaining a total pressure condition in a certain portion of the heat exchanger, which total pressure represents a relatively high partial pressure of the non-condensable gas constituent, and a relatively low partial pressure due to the condensable or vapor constituent with a consequent lowering of the temperature conditions of the vapor.

Another object of the present invention, therefore, is to effect an operation such that the partial pressure of the non-condensable constituents within the heat exchanger is increased in a controlled zone with a resulting decrease in the partial pressure of the condensable constituents, and the consequent vapor temperature of condensable constituents such that any condensate in contact with such zone may have its temperature lowered below the temperature of condensation.

In the accompanying figure of drawings, there is illustrated partly in section and partly in elevation, and largely diagrammatically, one form of apparatus by means of which the present invention may be carried out, it being understood that the drawings do not define the limits of my invention since changes in the construction and operation therein disclosed may be made without departing either from the spirit of the invention or the scope of my broader claims.

In accordance with the present invention, there may be provided a condenser shell 2 of any desired construction, having formed therein at some suitable point an inlet 3 for the vapor mixture to be condensed, and also being provided with a suitable outlet 4 from which condensate may be withdrawn to a suitable point of use.

While the specific construction of the condenser is relatively immaterial, the figure illustrates diagrammatically a condenser provided with a floating head 5 and with tubes 6 so arranged as to provide a double pass condenser. Cooling liquid may be supplied to

the tubes through the inlet 7 and after passage therethrough may be withdrawn from the apparatus through the outlet 8. The inlet and outlet may be formed in a header assembly 9 of any desired construction as well understood in the art.

If desired, baffles 10 of any desired construction, length and arrangement may be provided within the shell of the apparatus for insuring a flow of vapors and gases through the heat exchanger in a generally longitudinal direction accomplished by a series of successive transverse paths.

At a point intermediate the vapor intake 15 3 and the condensate outlet 4 there may be provided a gas offtake 11 which may comprise a single connection with the intertube or condensing space within the shell or which may comprise a series of longitudinally spaced connections such as indicated at 12. These connections may each communicate with a separate evacuating mechanism in the event the apparatus is to be operated at a pressure below atmospheric, or may separately communicate with the atmosphere in the event of an operation at atmospheric pressure, or they may be connected to a common connection 13 as may be desired. In any event, a separate regulating valve 14 will be 25 provided for each of the offtakes whereby any desired offtake may be brought into use at will to the exclusion of the others.

For purposes of illustration it may be assumed that the valve controlling the offtake 25 12 is closed while the valve controlling the offtake 11 is open. With the heat exchanger in normal operation such as occurs in the handling of vapors resulting from the distillation of oils, at least partial condensation of the vapors will have been obtained by the time they have traveled to a point adjacent the offtake 11. Some of the gases will therefore be drawn out at this point, together with some small amount of vapor, while the remaining portion of the uncondensed vapor mixture will travel onwardly as indicated by the arrows where condensation proceeds. Inasmuch as there is no gas offtake for this portion of the condenser, however, gas remaining 40 after the condensation of the vapors will accumulate in the portion below the offtake 11, and as condensation progressively continues, the partial pressure due to vapor will gradually decrease while the partial pressure due 45 to gases of a noncondensable nature will gradually increase, the total pressure remaining substantially constant. By reason of this condition, the temperature of the atmosphere of vapor and gases adjacent the terminus of 50 vapor flow through the condenser will be materially lowered. Correspondingly, condensate dripping or flowing through this portion of the heat exchanger will have its temperature correspondingly lowered. The 55 relatively cool condensate may then be with-

drawn from the condensate outlet 4, the cooling being further effected by the contact of the condensate with the relatively cold tubes through which the circulating fluid is passed.

The point of gas offtake, therefore, may be considered as dividing the vapor space of the unit into a condensing zone and a cooling zone, the offtake constituting either an imaginary or real division between these two zones. By placing the point of gas offtake closer to the vapor inlet, the capacity of the condensing zone is correspondingly reduced, while the capacity of the cooling zone is increased. Such a condition would enable the obtaining of condensate having relatively lower temperatures. On the other hand, by placing the point of gas offtake more remote from the vapor inlet, exactly the opposite condition is effected and condensate of relatively higher temperature results. The position of the gas off-take therefore, may be varied in accordance with the amount of vapor which it is desired to condense and the temperature of the condensate which it is desired to produce. The present invention, as will be apparent to those skilled in the art, contemplates the positioning of the gas offtake in accordance with the relation which it is desired to produce between the condensing and cooling. This enables a single piece of apparatus to be effectively utilized for different operations, thereby minimizing the number of parts required for the commercial adaptation of the invention, with a corresponding cheapening of the manufacturing costs by reason of the standardization of the major elements of the apparatus.

Certain advantages of the present invention arise from the provision of a heat exchanger so constructed as to provide a condensing zone and a cooling zone, and more particularly from an apparatus in which such zones are effectively produced by the positioning of a gas offtake intermediate the point of vapor inlet and condensate outlet.

Still other advantages of the invention arise from the provision of a unitary condensing apparatus so constructed as to permit effective control of the condensation and cooling, together with a desired variation in either of these conditions.

I claim:

1. In a heat exchanger, a condensing zone, a cooling zone, a plurality of individually controlled gas offtakes effective intermediate said zones, and a condensate outlet for draining the condensate level substantially to the bottom of the cooling zone.

2. In a heat exchanger, a condensing zone, a cooling zone, each of said zones comprising a combined vapor and gas space, and means for varying the effective area of at least one of said zones.

3. In a heat exchanger, a condensing zone,

- a cooling zone, means for varying the effective area of both of said zones, and a condensate outlet for draining the condensate level substantially to the bottom of the cooling zone.
5. In a heat exchanger, a condensing zone, a cooling zone, said zones having a serial flow of vapor therethrough, a plurality of gas off-takes located in stepped relation in regard to the vapor and gas flow and defining said zones, and means effective at will for rendering any desired offtake inoperative.
10. In a tubular heat exchanger, a condensing zone, a cooling zone, a plurality of gas off-takes located in stepped relation in regard to the vapor and gas flow and defining said zones, and means effective at will for rendering any desired offtake inoperative.
15. In the method of operating heat exchangers, the steps consisting of providing a vapor inlet and a condensate outlet, removing non-condensable gas at a point intermediate said inlet and outlet and at a distance substantially spaced therefrom to provide 20 distinct condensing and cooling zones, and varying the point of gas removal to vary the effectiveness of said zones.
25. In a heat exchanger, a condensing zone, a cooling zone, means for varying the effective area of at least one of said zones, and a condensate outlet for draining the condensate level substantially to the bottom of the cooling zone.
30. In the method of operating closed heat exchangers, the steps comprising supplying a cooling medium thereto, delivering the fluid to be condensed, withdrawing vapor and noncondensable gases therefrom, and varying the point of withdrawal to vary the 35 condensate temperature.
35. In the method of operating closed heat exchangers, the steps comprising supplying a cooling medium thereto, delivering the fluid to be condensed, and controlling the temperature of the condensate by increasing the partial pressure of the non-condensable gases in contact therewith.
40. In the method of operating closed heat exchangers, the steps comprising supplying a cooling medium thereto, delivering the fluid to be condensed, controlling the temperature of the condensate by increasing the partial pressure of the non-condensable gases in contact therewith, and varying the partial pressure of the non-condensable gases in contact therewith to vary the condensate temperature.
45. In testimony whereof I have hereunto set my hand.

60. **LAWRENCE M. FORNCROOK.**
